CLAIM

The ornamental design for a pedal, as shown and described.

DESCRIPTION

FIG. 1 is a top, rear perspective view of a pedal showing my new design;

FIG. 2 is front elevation view thereof;

FIG. 3 is a rear elevational view thereof;

FIG. 4 is a left side elevational view thereof;

FIG. 5 is a right side elevational view thereof; and,

FIG. 6 is a top plan view thereof.

The undisclosed bottom portion of the pedal has unornamented surfaces and forms no part of the claimed design. The claim is directed to raised features on the pedal. Portions of the pedal shown in broken lines are for illustrative purposes only and form no part of the claimed design.
